(57) **CLAIM**

I claim the ornamental design for a locker, as shown and described.

DESCRIPTION

FIG. 1 is a top perspective view of the locker embodying my new design as claimed herein.

FIG. 2 is a rear perspective view of the locker shown in FIG. 1.

FIG. 3 is a top view of the locker shown in FIG. 1.

FIG. 4 is a bottom view of the locker shown in FIG. 1.

FIG. 5 is a left side view of the locker shown in FIG. 1.

FIG. 6 is a right side view of the locker shown in FIG. 1.

FIG. 7 is a front view of the locker shown in FIG. 1.

FIG. 8 is a rear view of the locker shown in FIG. 1; and, FIG. 9 is a top perspective view of the locker shown in FIG. 1 in combination with a clamp.

The broken line showing of the locker is included for showing portions of the article and forms no part of the claimed design.
